UNITED STATES PATENT OFFICE.

CHARLES B. SCOTT, OF PHILADELPHIA, PENNSYLVANIA, AND HARRY E. FOSTER, OF MEDFORD, OREGON.

METAL POST AND POLE.

1,115,588.

Specification of Letters Patent.

Patented Nov. 3, 1914.

Application filed April 30, 1913. Serial No. 764,682.

To all whom it may concern:

Be it known that we, CHARLES B. SCOTT, residing in the city of Philadelphia, Pennsylvania, and HARRY E. FOSTER, residing in the city of Medford, Oregon, both being citizens of the United States, have invented new and useful Improvements in Metal Posts and Poles; and we do declare the following to be a full, clear, and exact description of the invention, such as will enable others skilled in the art to which it appertains to make and use the same, reference being had to the accompanying drawings.

Our invention relates to metal posts and poles adapted to be formed in sections or segments, preferably of sheet metal and adapted for use as telegraph poles, telephone poles, etc., and which will be strong and durable as well as highly efficient and effective in use.

An object of the invention is to provide posts and poles of this character which may be employed as fence posts and gate posts and for various other purposes and which are constructed to withstand thrusts and strains to which such posts are subject.

A further object is to provide posts and poles of this type which will be formed of the minimum number of parts of simple construction and which will be strong and durable as well as highly efficient and cheap to manufacture.

With the above and other objects in view, our invention consists in certain novel constructions, combinations, and arrangements of parts to be hereinafter more fully described, claimed, and illustrated in the accompanying drawings, in which,

Figure 1 is a detail perspective view of one of the segments employed in the construction of our improved posts and poles; Fig. 2 is an elevational view of the complete device employed as a telegraph pole constructed of the preferred form of segments; Fig. 3 is a plan view of the form of post shown in Fig. 2 with the cap removed; Fig. 4 is a cross-sectional view through this form of post; Fig. 5 is a fragmentary detail sectional view on the line 5—5 of Fig. 4; Fig. 6 is a view similar to Fig. 4, showing a different form of reinforcing means for the post; Fig. 7 is a fragmentary detail view with parts broken away to more clearly illustrate the form of reinforcing means shown in Fig. 6; Figs. 8 and 9 are detail

views of one of the reinforcing rods shown in Figs. 6 and 7; Figs. 10 and 11 are detail views of one of the stop nuts employed upon the reinforcing rods; Figs. 12, 13 and 14 are detail views of the lock washers employed upon the reinforcing rods; Fig. 15 is a view similar to Fig. 1 showing a modified form of segments; Fig. 16 is a cross-sectional view through the post constructed of the modified form of segments.

Referring more specifically to the drawings in which similar reference characters designate corresponding parts throughout the several views, 1 designates the segments or sections employed to form the body of our improved posts or poles and by referring to Fig. 1, it will be noted that the segments or sections are in the form of rectangular plates of metal or the like curved transversely, and by referring to Figs. 3 and 4, it will be seen that these segments or plates are placed with their concave faces positioned outwardly to form the outer face of a substantially triangular post, three of the segments or plates being employed for each length or section of the post or pole. It will be understood, however, that the plates may be of such length as to extend from one end to the other of the post or pole instead of forming the post or pole in sections. The longitudinal edges of the segments or plates are secured together by the rivets 2 or other suitable means, as clearly shown in Figs. 3 and 4. When the post is formed in sections, the lower horizontal edges of the segments or plates forming each section above the lowermost section are secured to the uppermost edges of the segments or plates forming the section therebeneath, by means of the rivets 3, or the like, it being understood that the segments or plates 1 preferably taper toward their upper ends, thereby making it possible for the lower edges of said segments or plates to be engaged outwardly of the upper edges of the segments or plates therebeneath. The lower edges of the segments or plates forming the lowermost section are bent outwardly at an angle, to form the base flanges 4 to assist in retaining the post or pole in upright position. The upper end of the uppermost section is closed by the cap 5 which is snugly engaged over the upper ends of the segments or plates 1 forming said uppermost section.

An ordinary cross arm 10 of an ordinary telegraph post or pole is secured against one side of our improved post or pole by the T-bolts 11 engaged therethrough and through opposite corners or longitudinal edges of the post or pole and having the nuts 12 threaded thereon while the heads of said T-bolts are engaged against opposite sides of our improved post or pole, thereby preventing rotation of the bolts 11.

When the post or pole is to be subjected to great strain and the strength of the post or pole must therefore be increased, the segments or plates 1 may be increased in thickness and the post or pole may be reinforced by the reinforcing core member 13 placed inside of each section of the post and having three concave faces conforming to the inner faces of the segments or plates 1 and also having three straight portions between the curved faces thereof. The three concave faces of the reinforcing core member 13 are vertical and said member 13 has three inwardly directed horizontal walls 14 extended inwardly from the lower edges of the vertical concave faces thereof, thereby greatly increasing the strength of the reinforcing core member. The member 13 is held in position and drawn against the three inner walls of the post or pole by the rods 15 which extend inwardly through the concave walls of the post or pole and the corresponding walls of the reinforcing core member and have their inner threaded ends engaged through the opposite straight portions of the reinforcing core member.

In Figs. 6 to 14, inclusive, we have shown another form of reinforcing means which consists of reinforcing I-bolts 16 which have their threaded ends projected through elongated vertical openings 17 in the concave walls of the post or pole and have the nuts 18 engaged thereon. Beneath the nuts 18 are washers 19 which have spaced lugs 20 upon their inner faces and adapted for engagement through the elongated openings 17. Threaded upon the reinforcing I-bolts 16 within the post or pole are the stop nuts 21 insertible through the elongated openings 17 which have concave outer faces conforming to the curvature of the inner faces of the segmental plates and adapted to be engaged by the same, thereby limiting inward movement of the sides of the post or pole and forming a rigid and reinforced structure. It will be seen that the reinforcing I-bolts 16 are crossed and the opposite or inner ends thereof are securely retained in position by the anchor bolts 22 engaged transversely through the corners or longitudinal edges of the post or pole and through the eyes 23 of the I-bolts 16, said anchor bolts 22 being secured in position by the nuts 24 or other suitable means. It will be evident that as the anchor bolts 22 are engaged through the

eyes of the reinforcing I-bolts 16, rotation of the latter will be prevented and as the legs 20 on the washers 19 are engaged through the vertical elongated slots 17 above and below the stop nuts 21, rotation of said washers 19 and stop nuts 21 will also be prevented after the nuts 18 have been threaded upon the bolts 16 to proper position against the outer faces of the washers 19.

In the modified form of post or pole shown in Figs. 15 and 16, we have shown the segment or plate 1' as having one longitudinal edge 29 turned back toward the convex or inner face of said segment or plate. In assembling this form of segment or plate to produce the post or pole or a section thereof, the segments or plates are placed in the same position as in the preferred form with the concave faces turned outwardly and the smooth or straight longitudinal edge of each segment or plate is engaged in the turned back edge 29 of the adjacent segment or plate and the rivets 30 or other suitable securing members are engaged through said straight and turned back edges. The post or pole is reinforced by the corner reinforcing members 31 which are of substantially triangular form in cross-section and which have their narrow edges engaged between the interlocked straight and turned back edges of the segments or plates 1', whereby the rivets or other securing means 30 will also be engaged through the thin edges of the reinforcing members 31 to retain the same in proper position. A telephone or telegraph cross arm 32 of any ordinary or preferred construction may be secured against one side of the post or pole by the substantially V-shaped securing bracket member 33 which has its bight portion 34 engaged around one longitudinal edge of the post or pole while the outer extremities of its legs are extended parallel, as shown at 35, and engaged transversely through opposite sides of the post or pole and through the straight side thereof, said extremities also extending through the cross arm 32 having the nuts 36 or the like threaded thereon to retain the cross arm in position. It will be understood that the main portion 110 of the legs of the bracket member 33 are curved inwardly and against the opposite sides of the post or pole.

From the foregoing, it will be apparent that we have provided an improved and simplified form of metallic post or pole and which may be readily employed for various purposes and which will be highly efficient as well as strong and durable in use. It will also be evident that the post or pole may be made any desired length by employing the proper number of sections. It will therefore be understood that while we have shown the preferred embodiment of our invention, many minor changes in the details 130

of construction and arrangements of parts may be made within the scope of the appended claims without departing from the spirit of our invention or sacrificing any of the 5 advantages of the same.

What we claim is:—

1. A device of the character described comprising a post formed of a plurality of plates, the longitudinal edges of the plates 10 being engaged one with the other, each of said plates being provided at predetermined points with elongated openings, anchor bolts disposed through the post adjacent the corners thereof, reinforcing bolts engaged with 15 said anchor bolts and projecting through the elongated openings, said projected portions of the reinforcing bolts being threaded, a stop nut threaded upon each of the reinforcing bolts and in contact with the inner face 20 of a plate, and clamping means engaging the projected extremity of each of the reinforcing bolts, said means including a washer provided with projections adapted to be accommodated within an elongated opening.
- 25 2. A device of the character described comprising a post formed of a plurality of

plates, the longitudinal edges of the plates being engaged one with the other, each of said plates being provided at predetermined points with elongated openings, anchor bolts 30 disposed through the post adjacent the corners thereof, reinforcing bolts engaged with said anchor bolts and projecting through the elongated openings, said projected portions of the reinforcing bolts being threaded, a stop nut threaded upon each of the reinforcing bolts and in contact with the inner face 35 of a plate, and clamping means engaging the projected extremity of each of the reinforcing bolts, said means including a washer provided with projections adapted to be accommodated within an elongated opening, said stop nut being insertible through an elongated opening.

In testimony whereof, we affix our signatures in presence of two witnesses.

CHARLES B. SCOTT.
